[22] Filed: Jan. 4, 1993

D. 87,081 5/1932 Pike D12/91

Primary Examiner—James M. Gandy
Attorney, Agent, or Firm—Mark P. Calcaterra

[57] CLAIM

The ornamental design for an automobile body, as shown and described.

DESCRIPTION

FIG. 1 is a front perspective view of an automobile body showing our new design, it being understood that the broken lines are for illustrative purposes only and form no part of the claimed design;

FIG. 2 is a rear perspective view of the automobile body shown in FIG. 1;

FIG. 3 is a side elevational view of the automobile body shown in FIG. 1;

FIG. 4 is a side elevational view of the automobile body shown in FIG. 1 with the convertible top down;

FIG. 5 is a top perspective view of the automobile body shown in FIG. 1;

FIG. 6 is a front elevational view of the automobile body of FIG. 1; and,

FIG. 7 is a rear elevational view of the automobile body of FIG. 1.
